UNITED STATES PATENT OFFICE.

ROBERT HANSON, ROBERT HENSHALL, AND ARTHUR EDWIN BOARDMAN,
OF WARRINGTON, ENGLAND.

WATER-TUBE BOILER.

SPECIFICATION forming part of Letters Patent No. 716,032, dated December 16, 1902.

Application filed March 31, 1902. Serial No. 100,768. (No model.)

To all whom it may concern:

Be it known that we, ROBERT HANSON, boiler-maker, residing at 33 Willis street, ROBERT HENSHALL, provision merchant, residing at The Old Vicarage, Knutsford road, and ARTHUR EDWIN BOARDMAN, engineer, residing at 78 Manchester road, Warrington, in the county of Lancaster, England, subjects of the King of Great Britain and Ireland, have invented certain new and useful Improvements in Water-Tube Boilers, (for which we have made application for Letters Patent in Great Britain No. 21,753, bearing date October 29, 1901,) of which the following is a specification.

This invention relates to water-tube boilers, the object being to provide a boiler affording effective circulation of water and efficient generation of steam with economy of fuel consumption, the construction of the boiler also admitting of free expansion and contraction of the tubes, and the boiler further, when necessary, effecting a drying or superheating of the steam.

The invention consists in arranging two or more steam and water drums above two or more water-drums between, but below which latter a set of fire-bars is disposed, and in connecting the upper drums to the lower, first, by groups of curved diagonal uptake water-tubes having the individual sets of each group alternating with each other, and, secondly, by curved lateral downtake water-tubes, the upper drums being further connected by large tubes to a dry-steam drum or superheater, and the whole boiler we inclose within a suitable casing provided with baffles in order to direct the gases of combustion, first, along a central inward flue among the diagonal uptake-tubes; secondly, along in an outward direction among the lateral side or downtake-tubes, and, thirdly, returning in an inward direction along the lower side flues in contact with a portion of the lower drums to the chimney or uptake-shaft.

The accompanying drawings illustrate one convenient manner of carrying out the invention.

Figure 1 is a front sectional elevation on B B of Fig. 2, which is a side sectional elevation on A A, Fig. 1. Fig. 3 is a sectional plan

on C C, Fig. 1, the boiler being removed in order to show the flues.

In carrying out the invention according to one modification and as illustrated in the drawings two steam and water drums *a a* are mounted above two lower water-drums *b b*. The drums *a a* are connected to the drums *b b* by groups *c d* of curved diagonal water-tubes, each set of tubes of one group alternating with each set of the other, as shown in Figs. 1 and 2. The upper and lower drums are further connected by lateral groups of water-tubes *e e*.

An upper steam-drum *g*, communicating with the drums *a a* by one or more large tubes *ff*, serves as a dry-steam drum or superheater. The whole boiler thus formed is inclosed within a casing *h*, provided with flues *k o*, formed by suitable baffles or walls *l p*. The furnace *m* is situated between but below the lower drums *b b*. The boiler is provided with blow-off pipes *i i*, which act as sediment-receivers, and with the usual mountings, cocks, and other fittings. A feed-water pipe *n* is led above the furnace, as shown, in order to heat the feed-water.

In operation the flames and gases of combustion passing inwardly and upwardly from the furnace *m* impinge upon the uptake-tubes *c d* and drums *a a*, quickly heating the water therein and setting up a rapid circulation, which induces an extensive generation of steam. The combustion-gases then pass outwardly, as shown by the arrows *x*, into the side flues *o*, where they meet the lateral downtake-tubes *e e*, down which the cooler water circulates from the upper to the lower drums. From the flues *o* the gases again pass inwardly, as shown by arrows *y y*, along the lower flues *k k* in contact with the lower drums *b b*, finally making an exit by the chimney or uptake-flue *j*, as shown by the arrows *z*. By this arrangement of flues the heat of the combustion-gases is most effectively utilized.

By arranging that the tubes *c d* cross each other and alternate in the manner shown above the furnace we insure great heat being applied at this part, as the tubes thereby form a baffle. The tubes being curved provide for free expansion and contraction and by their

crossing diagonally immediately above the furnace enable the hot gases to impinge against their surfaces during the passage through the central flue, while the provision of the return-tubes *e e* at the sides insures a complete circulation. The curved form of the tubes enables the ends to be rigidly secured to the upper and lower drums, any expansive movement being taken up by the curved form.

10 The tubes are all curved, preferably, to the same radius. The hot gases passing above the tubes *c d* impinge upon the drum *g* and dry or superheat the steam therein. When it is not desired to superheat the steam, the drum *g* may be protected by a baffle or fire-brick arch and then used simply as an ordinary collecting-drum.

15 It is to be understood that our invention is not confined to two upper and two lower drums, as any suitable number of these may be employed connected by tubes similarly to the manner hereinbefore described.

Having now described our invention, what we claim as new, and desire to secure by Letters Patent, is—

In combination, a water-tube boiler comprising two upper steam and water drums and two lower water-drums, two groups of curved diagonal uptake water-tubes connecting the upper drums to the lower, the individual sets of each group alternating, curved lateral downtake water-tubes connecting each upper drum to the lower drum immediately beneath, a dry-steam drum or superheater connected to the upper drums by one or more large tubes 35 and a set of fire-bars between but below the lower drums; and a boiler-setting comprising a casing *h*, baffles *l*, *p*, separating the central flue from side flues *o*, *o* and lower side flues *k*, *k* substantially as hereinbefore described 40 with reference to the accompanying drawings.

In witness whereof we have hereunto set our hands in presence of two witnesses.

ROBERT HANSON.

ROBERT HENSHALL.

ARTHUR EDWIN BOARDMAN.
